CLAIM

The ornamental design for a spray can actuator, as shown and described.

DESCRIPTION

FIG. 1 is a left side rear bird's eye perspective view of a spray can actuator showing our new design, and with a movable straw shown in a down position;

FIG. 2 is a left side front ant's eye perspective view the design of FIG. 1;

FIG. 3 is a rear view of the design of FIG. 1;

FIG. 4 is a front view of the design of FIG. 1;

FIG. 5 is a right side view of the design shown in FIG. 4;

FIG. 6 is a left side view of the design of FIG. 4;

FIG. 7 is a top view of the design of FIG. 4;

FIG. 8 is a bottom view of the design of FIGS. 6 and 7; and,

FIG. 9 is a left side front bird's eye perspective view of the spray can actuator of FIG. 1, and with the moveable straw shown in an up position.

In the drawings, the broken lines depict unclaimed subject matter only and form no part of the claimed design.

1 Claim, 6 Drawing Sheets
